his Attorney.

UNITED STATES PATENT OFFICE.

FREDERICK GROVER, OF LEEDS, ENGLAND, ASSIGNOR TO THE FORGROVE MACHINERY COMPANY LIMITED, OF LEEDS, ENGLAND.

CONTROLLING THE FEED OF CONTINUOUS-STRIP MATERIAL.

Application filed June 2, 1926, Serial No. 113,142, and in Great Britain October 26, 1925.

In Letters Patent No. 1,607,528 granted November 16, 1926, a machine for intermittently feeding a continuous strip to a severing device, where it is cut whilst stationary between two feeding operations, has been described. The purpose of the said machine was to separate the wrappers which had been printed on the continuous web, in correct register between the successive prints on the strip to be subdivided.

In this particular machine, the length of the portion of strip to be severed was corrected at each operation by bringing two electric contact feelers down on to the strip, one forward of the other, so that if the forward contact feeler passed through a registering aperture in the strip which coincided with the printed impression, then the strip would be given a shorter feed on the next operation. If, on the other hand, the rear contact feeler passed through the hole in the strip, then the next feed would be increased. Both these correcting operations were effected by contact feelers completing an electric circuit which determined the position to right or left of a magnet-operated arm located in the feed mechanism, and which by one or other of the contact feelers selected whether the longer or the shorter feed should be given.

The lengthening or shortening of the feed was effected by drawing back the strip after each cutting operation, by a small degree of reversal of the strip feeding rollers, the increase or decrease of this reversal being controlled by the position of the magnet operated arm.

The present invention provides means whereby a constant length of strip is normally fed at each operation, and correcting mechanism to increase or decrease a single feed is only introduced when sufficient error in length of feed has accumulated. Thus, by carefully adjusting the normal length of feed, the correcting apparatus is only brought into operation after a number of lengths have been fed forward, and when an error of plus or minus, having gradually

accumulated, becomes sufficient to require the correction to the feed.

In the drawings, Fig. 1 is a diagrammatic elevation illustrating the electrically controlled feed with the parts in the position for successively feeding similar lengths of strip.

Fig. 2 is a diagrammatic plan of the same apparatus, and Fig. 3 is a detail view.

In the drawings, K, K¹ are pivoted arms carrying metal brushes K³, K⁴. The arms K and K¹ are given a rise and fall motion so as to bring the brushes K³ and K⁴ simultaneously down on to the strip G at each operation while the strip is stationary. Equi-distant apertures in the strip permit the brushes K³ or K⁴ to complete electric circuits with a stud J located below the strip, should an aperture happen to be below either of the brushes K³ or K⁴ at the time when they are lowered. The distance between the brushes K³ and K⁴ is sufficient to permit an aperture in the strip G to rest between the said brushes when the strip is stationary, the distance being sufficient to allow for the aperture being somewhat in advance of the central position between the brushes, or somewhat behind the central position, without permitting one or other of the brushes to pass through and contact with the stud J.

The strip G passes between a pair of feed rolls D, D and intermittent motion is imparted to the feed rolls through a spur wheel A engaging one of a pair of gears carried by the feed rolls D, D.

The face of the wheel A is formed with an outstanding annular flange A² which is engaged by a rocking pawl C carried loosely in a notch in a boss C² and having an angular recess C¹ engaging the flange A². The rocking pawl C is normally held in position with its end in the notch in boss C² by a spring S'. The boss is loosely mounted on a stud axle, and is connected by a crank extension C^{2x} and connecting rod C³ with a crank on the main driving shaft of the machine (not shown) whereby the boss C² is

constantly reciprocated. An intermittent feed motion is given to the spur wheel when the rocking pawl C is moved in a clockwise direction by the boss C², the angular recess 5 gripping the flange A² and, through the gears, driving the feed rolls D D to feed the strip G forwardly.

If when the brushes K³ and K⁴ are lowered, the aperture in the strip happens to be 10 between the brushes, neither of the said brushes contacts with the stud J and no electrical circuit is completed. If, however, the brush K⁴ when lowered passes through the aperture and contacts with the stud J, a current is passed through a magnet N which 15 attracts an arm M of a lever which is carried upon an extension L³ of a lever L¹, causing the opposite arm M¹ of the lever to be rocked opposite to a notch O¹ in a member O. This member O is reciprocated by 20 means of a connecting rod C³, and when it is advanced the pawl C is moved in a counter-clockwise direction and passes freely over the flange A² of the spur wheel A 25 while the arm M¹ of the lever is received into the notch O¹, and pushes the said arm M¹, thereby rocking the lever L¹ which frictionally grips the spur wheel A. This 30 movement carries the spur wheel in an anti-clockwise direction and through gearing carried by the feed rolls D D reverses the direction of movement of the said feed rolls D D, thus causing the strip G to be drawn back a short distance. The notch O¹ being 35 the deepest of three notches O¹, O³, O², causes the member O to move the draw-back mechanism L¹, L³ to the minimum extent. The greatest length of feed is therefore 40 given to the strip G upon the next operation, and when the brushes K³, K⁴ are next lowered, the aperture is between the brushes K³, K⁴ and no contact is made.

The arm M¹ of the lever is centralized by 45 the rise of a fork S (see Fig. 3) which is secured to and projects upwardly from the crank extension C^{2x} of the boss C² and when the boss C² is rocked by the connecting rod C³ in a rearward direction the fork S rises and engages the under side of the arm M¹ 50 which is centralized by inclined faces formed in the fork. On the next throw of the connecting rod C³, the notch O³ in the member O is advanced to the lever arm M¹, and the draw-back mechanism L¹, L³ is therefore 55 moved the normal distance. This normal distance of draw-back following each feed continues until another error has accumulated sufficient to bring one of the brushes, say K³, to contact through an aperture with 60 the stud J. This causes the magnet N¹ to be energized and to attract the arm M of the lever so as to bring the arm M¹ opposite the shallowest notch O² in the member O. As 65 the member O advances, the arm M¹ of the lever being intercepted through a greater

distance of the throw of the member O, the draw-back mechanism L³ is moved to the maximum extent and the feed of the strip G is therefore reduced sufficiently to again bring the aperture centrally between the 70 brushes K³, K⁴ on the next occasion when they are lowered on to the strip.

The lever M, M¹ being centralized by the fork S, the end M¹ is again brought opposite the intermediate notch O³, causing the normal draw-back to be effected until an error has again accumulated sufficient to complete an electric circuit through one of the brushes K³ or K⁴.

Instead of the strip material being perforated, a mark or bar of electrically conducting material may be applied to the surface of the strip G. In such an arrangement each arm K and K¹ would carry duplicate brushes such as K³ and duplicate brushes such as K⁴, and when the duplicate brushes K³ or K⁴ contact with the mark or bar on the strip an electric circuit would be completed and one of the magnets N or N¹ energized without the necessity of the said 80 brushes communicating with a stud on the opposite side of the strip.

In correcting the feed of a strip which is itself of conducting material, marks or bars of non-conducting paint or other non-conducting surface may be applied to the strip at given intervals for the purpose of selecting whether a current be completed or not in accordance with the requirement of increasing or decreasing the length of feed to 90 be given to the strip.

What I claim as my invention and desire to secure by Letters Patent is:—

1. In apparatus for feeding lengths of strip material to register with impressions on the strip wherein mechanism is provided for increasing or decreasing the length of strip to be fed at each operation, a three position intercepting device in combination with a three stepped reciprocating member 105 adapted to coact with the three position intercepting device, whereby one of three lengths of feed is selected at each operation.

2. In apparatus for feeding lengths of strip material to register with impressions on the strip wherein mechanism is provided for increasing or decreasing the length of strip to be fed at each operation, the combination of a three position intercepting device, a three stepped reciprocating member adapted to coact with the three position intercepting device, and a fork carried on a rocking portion of the mechanism and located so as to engage the intercepting device to return it to the central position after a side position has been operated for correcting the length of strip delivered.

3. In apparatus for feeding lengths of strip material to register with impressions on the strip wherein mechanism is provided 130

for increasing or decreasing the length of strip to be fed at each operation, a three position intercepting lever, electromagnets for rocking the lever into a right or left position, a reciprocating member having notches formed in the face of said member to coact with said pivoted lever in any of its three positions, and a fork rocked at each opera-

tion to return the lever to the central position during the next operation following the 10 rocking of the lever to one side or the other side by one or other of the magnets.

In witness whereof I have hereunto set my hand.

FREDERICK GROVER.
